UNITED STATES PATENT OFFICE

WALLACE N. APPLETON, OF CRAFTON, PENNSYLVANIA, ASSIGNOR, BY MESNE ASSIGNMENTS, TO THE MCKAY COMPANY, OF PITTSBURGH, PENNSYLVANIA, A CORPORATION OF PENNSYLVANIA

GRINDING MACHINE

Application filed May 8, 1929. Serial No. 361,325.

My invention relates to grinding and polishing machines, and more particularly to those especially suitable for grinding and polishing metal bars, such as the front and rear bumper bars of automobiles.

In the manufacture of automobile bumpers of the flat bar type as distinguished from the tubular or channel bar bumpers, the bars are commonly formed of flat spring steel which is curved to the proper contour and frequently have a loop or eye formed in both ends thereof in the case of front bumper bars and formed in at least one end thereof in the case of rear bumper bars or fender guards.

If the bumper bars are to be plated with nickel, chromium, etc., it is necessary that they be quite smooth and this smoothing is effected by grinding and polishing the bars after they have been shaped to the desired form. Heretofore, it has been difficult to properly grind and polish curved bars, and bars with eyes formed in their ends, without considerable handwork, because of difficulty in polishing the bars in proximity to their eyes and in effecting uniform grinding and polishing through out the length of a curved bar.

One object of my invention is to provide an apparatus capable of more effectively grinding and polishing bars having loop or eye portions.

Still another object of my invention is to simplify and improve generally the art of grinding and polishing metal bars.

One form which my invention may take is shown in the accompanying drawings, wherein Figure 1 is a side elevational view of a grinding and polishing machine; Fig. 2 is a view taken on the line II-II of Fig. 1, on an enlarged scale; Fig. 3 is a horizontal sectional view of a portion of the apparatus of Figs. 1 and 2, and Fig. 4 is an elevational sectional view on an enlarged scale, of a portion of the apparatus of Fig. 1.

The apparatus consists of conveyer frame-

work 5 at the opposite ends of which are mounted pulleys 6 and 7 for driving a conveyer belt 8, the pulley 7 being driven from a suitable source of power by a driving pulley 9 and a driving belt 10. The upper flight 50 of the conveyer belt 8 is supported by a bearing block 11 of wood or other suitable material that is supported on the web of an I-beam 12 forming part of the upper framework of the conveyer. Guide rails 13 are 55 mounted upon the block 11 to prevent lateral displacement of the conveyer belt.

The conveyer belt 8 carries a series of brackets 14 that are secured thereto as shown more clearly in Figs. 2 and 4. A carrier arm 60 15 is pivotally secured to each of the brackets 14 and is forked at its outer end. A pin or rod 16 extends through the forked end of each arm 15 and such arm is normally held in the position shown in Fig. 4, by means of a 65 spring 17 that is anchored to a plate 18 which is secured to the bracket 14. One end of the rod 16 carries an anti-friction roller 19 that is held, through the action of the spring 17, in engagement with a cam bar 21, so that the 70 arm 15, under the action of the said spring and the said cam bar will oscillate about its pivot as hereinafter explained.

The other end of the pin 16 serves to receive the eye 22 of a bumper bar 23 and to 75 support the said bumper bar during movement thereof along the upper path of travel of the conveyer belt, the bar being manually slid into position upon the pin 16 at the right hand end of the conveyer as viewed in Fig. 1 80 and removed therefrom at the opposite end thereof.

Grinding and polishing wheels 25 and 26 are supported upon pedestals 27 and 28 respectively, and are driven by motors 29. 85 These grinding wheels may be of emery or other abrasive materials of a suitable fineness and the wheel 26 may contain a finer grade of abrasive than the wheel 25. The axes of the wheels 25 and 26 are fixed, and 90

there will be no problem of inertia of such wheels to overcome in causing them to bear against all parts of a curved bar.

As the bars 23 are connected to the carrier arms 15, they are carried beneath the grinding wheels 25 and 26. Idlingly-mounted presser wheels 31 and 32 are disposed beneath grinding wheels 25 and 26, respectively, and are supported upon crank arms 33 (Fig. 3) 10 that form extensions of sleeve-like bearing members 34 each of which is pivotally mounted upon a pin or shaft 35 that is secured to an upright 36. A drum-like extension 37 is secured to each of the presser wheels, 31 and 32, and each wheel is normally held in the position shown in Fig. 4 by means of a weight 38 that is connected, through a strap 39, to the drum, stop members 41 and 42 being provided on a post 43 and the drum 37, respectively, to limit backward rotative movement of the wheel under the influence of the weight.

A weight arm 44 is connected to the sleeve 34 and has notches therein wherein a weight 45 may be supported, at different positions longitudinally of the arm, to vary the upward pressure of the presser wheels, so that bumper bars will be held against the wheels 25 and 26 with a desired degree of pressure.

With the wheels 31 and 32 positioned as shown in Figs. 4 and 1, respectively, notches 46 provided therein will be in position to receive the eyes 22 of the bumper bars 23 and the pull exerted by such eyes, during advance 30 movement of the conveyer and the bumper bars will cause the presser wheels to be rotated and to press the bars 23 into engagement with the grinding wheels 25 and 26, the degree of pressure depending upon the position 35 of the weight 45 on the arm 44. As soon as a bumper bar has passed completely from engagement with the wheels 25 and 31, for instance, the wheel 31 will be returned to its normal position, under the action of the weight 38, ready to receive the eye of the succeeding bumper.

After the forward end of the bumper bar has passed from beneath the grinding wheel 25 and the wheel 26, the carrier arm 15 to 50 which said bar is connected will be deflected downwardly by the cam surfaces 21a and 21b of the bar 21, through contact of such surfaces with the roller 19, thus causing the bar to engage the grinding wheel 25 (for instance) only at points opposite to the wheel 31, and insuring that there will not be excessive polishing of the curved portion of the bumper through tendency of the arm 15 and the spring 17 to maintain it in too high a 55 plane after passing from between the wheels.

From the foregoing, it will be seen that not only are all the forwardly-exposed portions of the eye 22 fully ground and polished, but that all portions of the bar 23, whether 60 curved or straight, are polished to a uniform

degree by reason of the uniformity of pressure exerted thereon by the presser wheels 31 and 32 and by reason of the vertical movements of the carrier arms 15 previous to and after it passes the presser wheels and the 70 grinding wheels.

In the appended claims, it will be understood that the word "grinding" is employed in a broad sense to include also smoothing operations such as polishing or buffing. 75

I claim as my invention:

1. Grinding apparatus for bars having enlarged portions at one end, comprising a grinding wheel, a rotatably mounted presser member for holding work in engagement with said grinding wheel, a recess on said presser member for receiving the said enlarged portions of bars, a carrier for the bars, and means for returning the presser member to initial position after it has been rotated by passage 85 of the said enlarged portions.

2. Grinding apparatus for bars having enlarged portions at one end, comprising a grinding wheel, a rotatably mounted presser member engaging against the under-surface 90 of the work for holding work in engagement with said grinding wheel, a recess on said presser member for receiving the said enlarged portions of bars, a carrier for the bars, stop means for holding said presser member in position to receive said enlarged portions of the bars, and means for yieldably holding said member against said stop.

3. Apparatus for grinding a metal bar having an offset portion on one end thereof, 100 comprising a grinding wheel, a conveyer, an outwardly-extended carrier arm on said conveyer movable relatively to the conveyer and having means thereon for engaging said offset portion, and means disposed adjacent to 105 the grinding wheel and affording support for the other portions of the bar during movement past said wheel.

4. Apparatus for grinding curved bumper bars having eye portions in one end thereof, 110 comprising a grinding wheel, a conveyer, carrier arms on the conveyers having means for effecting detachable connection with said eye portions, means for yieldably urging said arms outwardly to effect grinding engagement between the said eye portions and the 115 said wheel during traveling movement of the conveyer, and a presser member independent of the conveyer for supporting the other portions of the bars during movement 120 past said wheel.

5. Apparatus for grinding bars, comprising a grinding wheel, a presser member for holding the bars in engagement with said wheel, a conveyer for continuously advancing the bars between the said member and the said wheel, outwardly-extended carrier arms on the conveyer for pivotally supporting one end of the bars, and means for yieldably projecting said arms. 125

6. Apparatus for grinding bars, comprising a grinding wheel, a presser member for holding the bars in engagement with said wheel, a conveyer for continuously advancing the bars between the said member and the said wheel, outwardly-extended carrier arms on the conveyer for pivotally supporting one end of the bars, means for yieldably projecting said arms, and means for depressing the said arms to change the angular position of the bars relative to the grinding wheel during a grinding operation.

In testimony whereof I, the said WALLACE N. APPLETON, have hereunto set my hand.

WALLACE N. APPLETON.
